UNITED STATES PATENT OFFICE.

GEORGE F. GRUBE, OF EVANSTON, ILLINOIS, ASSIGNOR TO THE BELBER TRUNK & BAG COMPANY, OF PHILADELPHIA, PENNSYLVANIA, A CORPORATION OF PENNSYLVANIA.

WARDROBE TRUNK.

1,469,707.

Specification of Letters Patent. Patented Mar. 14, 1922.

Application filed January 27, 1919. Serial No. 273,212.

To all whom it may concern:

Be it known that I, GEORGE F. GRUBE, a citizen of the United States, residing at Evanston, county of Cook, and State of Illinois, have invented a new and useful Improvement in Wardrobe Trunks, of which the following is a full, clear, and exact description, reference being had to the accompanying drawings, which form a part 10 of this specification.

The object of my invention is to provide a means for simultaneously locking and unlocking a plurality of drawers in a compartment of a wardrobe trunk.

15 A preferred embodiment of my invention is shown in the accompanying drawings, in which—

Fig. 1 is a perspective view of a trunk with my improved drawer locking device applied thereto.

20 Fig. 2 is a partial front view of the drawer compartment showing the locking device open.

Fig. 3 is a horizontal section showing the 25 locking device in plan.

Fig. 4 is a partial section through the compartment on line 4—4 of Fig. 3, drawn on a larger scale.

The trunk comprises, as is usual, two compartments *a* and *b*, hinged together, the first compartment being occupied, in whole or in part, by a set of drawers, and the second compartment being provided with supports for garment hangers or adapted 35 for any other desired use. My invention relates only to that compartment provided with drawers.

The last named compartment, *a*, which is a box-shaped frame, preferably of wood, is 40 provided with metal flanges or strips *c* which project beyond the edges of the wooden frame and interlock with the other compartment when the trunk is closed. The compartment *a* is also provided with spaced- 45 apart supports *d*, which are shown as solid horizontal partitions, but may assume any form so long as they support the drawers *e* and permit them to be independently slid into open and closed position.

50 Extending along each vertical edge of the compartment *a* is a locking bar or strip *f*, which is shown in hinged relation thereto. Preferably, the hinges are located at the angle or corner formed between the outer 55 edge of the wooden frame or body and the

inner face of the contiguous metal flange *c*. These locking bars, being pivoted on axes extending longitudinally thereof, may be swung inward so as to overlap the drawers, when closed, and prevent their withdrawal; 60 or may be swung outward against the inner faces of the flanges *c*, in which position the drawers are free to be withdrawn.

Pivoted on horizontal axes to the upper ends of the respective locking bars are bars 65 *g* and *h*. The upper drawer of the series of drawers is preferably provided with a transversely extending recess or depression *i* to receive the bars *g* and *h*. Bar *g* is provided with a slot or hole *j* and bar *h* with a pin 70 *k* adapted to engage the slot *j*. Bar *h* also carries a lock, or locking hasp, *m*, which is adapted to fit within a hole *n* in the front of the upper drawer and is provided with a key-actuated sliding bolt adapted to engage 75 an adjacent recess, which may be conveniently formed in the lower wall of that part of the frame or body *a* overhanging the upper drawer.

The construction, as described, is manipulated as follows. Assuming that the mechanism is in locking position: The lock *m* is first operated to unlock the bar *h*. Both bars *g* and *h* are therefore now free, together with the bars *f*, to swing outward 85 on the vertical axes of the bars *f*, after which the bars *g* and *h* may be swung or dropped down on their own horizontal axes so as to lie alongside the bars *f*. The drawers are now free to be independently withdrawn. 90 To lock the drawers in position after they are replaced, the bars *g* and *h* are swung up on their own axes into about a horizontal position and are then swung in toward the upper drawer, thereby swinging in the bars 95 *f* into position to prevent the withdrawal of the drawers. When the bars *g* and *h* have moved into their innermost position they fit into the recess *i* and therefore lie flush with the upper drawer, pin *k* engages slot *j*, and 100 lock *m* engages hole *n*. The bolt of the lock is then operated to secure the bar *h* in position, thereby locking in position the entire series of bars *g*, *h*, *f*, and preventing the withdrawal of the drawers.

Having now fully described my invention, what I claim and desire to protect by Letters Patent is:

1. In a trunk, the combination with a trunk compartment, of drawers therein ar- 110

ranged one above another, a pair of vertically extending bars arranged along opposite sides of the compartment and pivotally mounted thereon so as to swing into and 5 out of the path of the drawers, bars pivotally attached on horizontal axes to the first named bars and adapted, when swung upward on their axes and when the first named bars are swung into the path of the 10 drawers, to span the space across the drawers, and means to lock the second bars in fixed relation with the trunk compartment when said bars are in the positions specified.

2. In a trunk, the combination with a 15 trunk compartment, of drawers therein arranged one above another, a pair of vertically extending bars arranged along opposite sides of the compartment and pivotally mounted thereon so as to swing into and 20 out of the path of the drawers, bars pivotally attached on horizontal axes to the first named bars and adapted, when swung upward on their axes and when the first named bars are swung into the path of the 25 drawers, to extend in front of the drawers, and a single locking contrivance adapted, when said bars are in the positions specified, to lock all the bars in said positions.

3. In a trunk, the combination with a 30 trunk compartment, of drawers therein arranged one above another, a pair of vertically extending bars arranged along opposite sides of the compartment and pivotally mounted thereon so as to swing into and out 35 of the path of the drawers, and bars pivotally attached on horizontal axes to the first named bars and adapted, when swung upward on their axes and when the first named bars are swung into the path of the 40 drawers, to engage each other.

4. In a wardrobe trunk, the combination 45 with a trunk compartment, of a tier of drawers thereon arranged one above the other and each extending horizontally when the trunk is stood on end, a drawer-end lock-

ing contrivance comprising two longitudinally and vertically extending bars arranged along opposite sides of the compartment and pivotally mounted thereon so as to swing into and out of the path of the drawers, means pivotally attached to the drawer-end locking contrivance and adapted to be swung upward and inward and to span the space across the tier of drawers, and means to retain the parts in locking 50 position.

5. In a trunk, the combination with a 55 trunk compartment, of drawers therein arranged one above another, a pair of vertically extending bars arranged along opposite sides of the compartment and pivotally mounted thereon so as to swing into and out of the path of the drawers, cross bars pivotally attached to the respective first named bars and whose free ends are adapted to 60 engage each other, and a locking contrivance carried by one of the second named bars, the upper drawer having a transversely extending depression to receive the second named bars and a recess to receive the locking 65 contrivance.

6. In a trunk, the combination with a 70 trunk compartment, of drawers therein arranged one above another, a pair of vertically extending bars arranged along opposite sides of the compartment and pivotally mounted thereon so as to swing into and out of the path of the drawers, bars attached 75 to the first named bars and adapted when the first named bars are swung into the path of the drawers to span the space across the drawers, and means to lock the second bars in fixed relation with the trunk compartment when said bars are in the position 80 specified.

85 In testimony of which invention, I have hereunto set my hand, at Chicago, Illinois, on this 22nd day of January, 1919.

GEORGE F. GRUBE.
